DESIGN FOR AIRPLANE

Antonio Cernuda, Habana, Cuba

Application June 16, 1936, Serial No. 63,329

Term of patent 7 years

To all whom it may concern:

Be it known that I, Antonio Cernuda, a citizen of Cuba, residing at Habana, Cuba, have invented a new, original, and ornamental Design for an Airplane, of which the following is a specification, reference being had to the accompanying drawing, forming part thereof.

In the drawing:

Fig. 1 is a top plan view of an airplane embodying my new design.

Fig. 2 is a side elevational view; and

Fig. 3 is a perspective view of the same airplane.

I claim:

The ornamental design for an airplane, as shown,

ANTONIO CERNUDA.
